UNITED STATES PATENT OFFICE.

CHARLES C. PARK, OF SIOUX FALLS, SOUTH DAKOTA.

SPOKE-TIGHTENING JACK.

Application filed February 1, 1926. Serial No. 85,216.

This invention relates to certain new and useful improvements in spoke tightening jacks and the primary object thereof is to provide a jack of this type which is of simplified and economical construction, which is of easy and positive operation, and which employs a minimum of parts compactly assembled.

In the drawings:—

10 Fig. 1 is a side edge elevation of the invention applied to a wheel, the latter shown in fragment;

Fig. 2 is a section on line 2—2 of Fig. 1;

15 Fig. 3 is a section on line 3—3 of Fig. 2; and

Fig. 4 is a section on line 4—4 of Fig. 2.

In proceeding in accordance with the present invention, a head or body 1 is provided having a nose 2 at its lower end 20 formed to engage the hub of the wheel the adjacent parts of two adjacent spokes as illustrated in Fig. 1 of the drawings. The body 1 has a pair of spaced parallel arms 3 projecting upwardly therefrom the arms 25 being each formed with two series of perforations 4, the perforations of the two series being relatively staggered and receiving a pivotal pin 5 therein of the cam head 6 of lever 7.

30 A jaw 8 is slidably carried by and between the arms 3 and is formed with depressions 9 on its opposite side faces which form side flanges 10, the latter guidingly engaging the arms 3. The jaw 8 has a longitudinal slot 11 through which a pin 12 secured to the arms 3 projects so as to prevent disengagement of the jaw and the body 1.

The cam 6 acts directly on and against the lower end of the jaw 8 and by removing 40 pin 5 and placing same in the desired perforations of the arms 3, the jack may be adjusted to wheels of varying diameters.

In use, the desired adjustment is first made, whereupon the nose 2 and jaw 8 are 45 engaged with the hub and felloe respectively and lever 7 moved downwardly to move the felloe away from the spoke and the shoulder of the latter, whereupon a collar or packing is introduced between the 50 shoulder and felloe to thus tighten the spoke.

What is claimed is:—

In a spoke tightening jack, a body having 55 a head formed with a nose, a pair of spaced arms projecting outwardly from the head and each formed with a series of perforations, a substantially U-shaped jaw having its arms connected by a relatively thin centrally disposed web, adapted to form depressed portions forming guide flanges which engage the sides of the arms of the head, said web having a longitudinal slot, 60 a pin carried by the arms of the head and extending through said slot, a pin engageable in selected perforations of the arms of the head, and a lever having a cam pivotally supported by the last named pin between the arms and engaged with the inner end 65 of the jaw.

In testimony whereof I affix my signature.

CHARLES C. PARK.
